AUTOMOBILE BODY

Karl Wilfert, Gerlingen-Waldstadt, Germany, assignor to
Daimler-Benz Aktiengesellschaft, Stuttgart-Unterturk-
heim, Germany

Filed Mar. 5, 1968, Ser. No. 10,855

Claims priority, application Germany Sept. 6, 1967

Term of patent 14 years

Int. Cl. D12—08

U.S. Cl. D14—3

FIGURE 1 is a front perspective view of the automobile body showing my novel design;

FIGURE 2 is a rear perspective view thereof;

FIGURE 3 is an elevational view taken from the side shown in FIGURE 1;

FIGURE 4 is a front view thereof;

FIGURE 5 is a rear view thereof.

The left side of the automobile is similar to the right side shown in FIGURE 3.

The characteristic features of my novel design reside in its low and wide radiator grille, in its headlights which are delimited laterally and at the top by curved lines with relatively large radius of curvature, in the body contours of the hood and body panels adjoining the radiator grille and side fenders, in the relatively wide and long main front bumper extending uninterruptedly from one side of the vehicle to the other and in the relatively short and narrow lower front bumper interrupted in the center

to accommodate the license tag, all as seen in front views, and in the single rear bumper extending laterally only slightly around the rear of the vehicle, as seen in the rear and side perspective views.

The wheels and tires shown in broken lines are included for illustrative purposes only.

I claim:

The ornamental design for an automobile body, as shown and described.
